UNITED STATES PATENT OFFICE.

GEORGE A. WATSON, OF TORONTO, CANADA.

BOOT AND SHOE HOLDING APPLIANCE.

No. 795,871

Specification of Letters Patent.

Patented Aug. 1, 1905.

Application filed November 4, 1902. Serial No. 130,100.

To all whom it may concern:

Be it known that I, GEORGE A. WATSON, of the city of Toronto, in the county of York and Province of Ontario, Canada, have invented certain new and useful Improvements in Boot and Shoe Holding Appliances; and I hereby declare that the following is a full, clear, and exact description of the same.

This invention relates to that class of boot and shoe holding appliances designed to hold a boot or shoe while being cleaned and polished; and the object of the invention is to so arrange the apparatus that the toe member will laterally expand and completely fill the toe portion of the boot or shoe during the adjustment of the heel and toe members to clamp the shoe to the holder.

In carrying out the invention I employ a supporting element, to which is hinged an expanding toe member, and provide this supporting element with an adjustable heel member fitted with a locking device to hold it in its adjusted position, as hereinafter more fully set forth, and more particularly pointed out in the claims.

In the drawings, Figure 1 is a perspective view of the holding appliance. Fig. 2 is a perspective view of the toe member in an inverted position to show the expanding parts. Fig. 3 is a perspective view of the holding appliances with the toe member removed and with a portion of the sleeve broken away to show the construction of the lever and its toothed segment.

Like letters of reference refer to like parts throughout the specification and drawings.

The supporting element consists of a horizontal arm *a*, having at its front or outer end a depending arm *b* and along its top edge a rack *c*, the front end of the top edge being provided with a recess *d*. At the inner or rear end of the horizontal arm *a* is a depending hinge-pin *e*, adapted to enter the socket *f* of the hinge member *g*, arranged to be made fast to a wall or other supporting medium.

By reference to Fig. 1 of the drawings it will be noticed that the under side of the horizontal arm *a* at its junction with the hinge-pin *e* is fitted with a stop *h* and that a corresponding recess *i* is formed in the socket *f* to receive the stop *h* when the horizontal arm is in its forwardly-projecting position, the purpose of the stop *h* and recess *i* being to rigidly lock the bracket against lateral movement. Movable mounted on the horizontal arm *a* is the sleeve *j*, and integrally formed

with the sleeve *j* is the depending arm *k* for the heel member *l*. Journaled in the sleeve *j* is a toothed segment *m*, meshing with the teeth of the rack *c*, and integrally formed with the toothed segment *m* is a lever *o*. Pivotally connected to the sleeve *j* is a pawl *p*, arranged to engage the teeth of the rack *c* and lock the sleeve and heel member in their adjusted position. At the lower end of the depending arm *b* is a forwardly-projecting lug *q*, in the under side of which is a recess *r*, and projecting forwardly from the middle of the top of the lug *q* is the toe member *t* of the holding appliance. The toe member *t* consists of an expanding-wedge *u*, having an aperture *v* to receive the lug *q* and a hinge-pin *w* to enter the recess *r* in the under side of the lug. The aperture *v* is of such a shape and size as to allow of the entrance therein of the lug *q* when the toe member *t* has been turned into a substantially vertical position against the depending arm *b*, the toe member when lowered into the horizontal position shown in Fig. 1 engaging the front end of the lug. At the sides of the expanding-wedge *u* are the expandible side pieces *x*, provided with inwardly-directed flanges *y*, having longitudinal slots *z*, through which pass the guide-pins *a'*, connecting the expanding-wedge *u* to a guide-plate *b'*, located below the flange *y* to support the side pieces *x* and hold them relatively to the expanding-wedge, and formed in the flanges *y* are grooves *y'* to receive the flanges *y* of the expanding-wedge *u* and guide the movement of the side pieces *x* when moving into their expanded or contracted position.

In the use of the invention the toe member is inserted into the toe of the boot or shoe and turned into any position between the horizontal position shown in Fig. 1 of the drawings and a vertical position substantially parallel with the depending arm *b*, the hinging of the toe member to the arm in the manner above described providing an ankle motion for the toe member to facilitate its entry into the boot or shoe, the heel member at this time being placed contiguous to the depending arm *b* to enter the boot or shoe concurrently with the toe member. When the toe member has entered the boot or shoe, the heel member is adjusted relatively thereto, and the lever is turned rearwardly, as indicated by arrow, to move the heel member longitudinally and expand it against the heel of the boot or shoe, such expansion causing the toe and heel mem-

bers to rigidly grip the same. To further prevent the displacement of the boot or shoe from the toe and heel members, the laces are crossed and tied in the recess *d* with sufficient tension to resist the downward polishing pressure on and prevent the boot or shoe being forced from the holding appliance.

The toe member of the holding appliance expands as it enters the toe of the boot or shoe and completely fills it to remove the creases therein and enable it to be properly cleaned and polished.

By turning the lever *o* forwardly a sufficient distance the teeth of the segment will be disengaged from the rack and the sleeve *j*, with its depending arm *k*, may be moved freely on the horizontal arm *a* to any desired position.

Having thus fully described my invention, what I claim as new, and desire to secure by Letters Patent, is—

1. In a boot and shoe holding appliance, the combination of a supporting element, consisting of a horizontal arm having a depending arm connected thereto, provided at its end with a forwardly-projecting lug, having a recess on its under side, and a toe-engaging member provided with an aperture to receive the lug on the depending arm, and a hinge-pin to engage the recess on the under side of the lug, said toe-engaging member comprising a pair

of laterally-adjustable side pieces, a sleeve movable on the horizontal member toward and away from the depending arm connected to the horizontal arm, provided with a depending arm having a heel-engaging member thereon, and means for locking the sleeve on the horizontal arm.

2. In a boot and shoe holding appliance, the combination of a supporting element, consisting of a horizontal arm having a depending arm connected thereto provided at its end with a forwardly-projecting lug having a recess on its under side, and a toe-engaging member comprising a wedge and a pair of laterally-adjustable side pieces engaging the wedge and movable thereon, the wedge being provided with an aperture to receive the lug on the depending arm and a hinge-pin to engage the recess on the under side of the lug, a sleeve movable on the horizontal arm toward and away from the depending arm, provided with a depending arm having a heel-engaging member thereon, and means for locking the sleeve on the horizontal arm.

Toronto, September 29, 1902.

GEO. A. WATSON.
